UNITED STATES PATENT OFFICE.

MORRIES WEAVER, OF JONESTOWN BOROUGH, PENNSYLVANIA, ASSIGNOR TO JOHN T. BUCKWALTER, OF LANCASTER, PENNSYLVANIA.

GRAIN-SEPARATING MACHINE.

1,073,451.

Specification of Letters Patent. Patented Sept. 16, 1913.

Application filed January 20, 1911, Serial No. 603,683. Renewed February 18, 1913. Serial No. 749,280.

To all whom it may concern:

Be it known that I, MORRIES WEAVER, a citizen of the United States, residing in the borough of Jonestown, county of Lebanon, 5 and State of Pennsylvania, have invented certain new and useful Improvements in Grain-Separating Machines, of which the following is a specification.

My invention relates to improvements in 10 grain-separating machines wherein means are provided for cleaning wheat and other grains by separating cockles, chaff and other foreign materials therefrom, and has for its object to supply a machine of this character 15 which is comparatively simple in construction and is adapted to act efficiently upon grains of varying weight and to maintain a uniform blast pressure under any prearranged condition of adjustment without regard to variations in velocity of the moving 20 parts.

To this end and the accomplishment of such other objects as may hereinafter appear, the invention consists in the construction and combination of parts hereinafter 25 particularly described and claimed, reference being had to the accompanying drawings, in which:

Figure 1, is a central vertical sectional 30 view of a device embodying my invention. Fig. 2, is a sectional view on line 2—2 of Fig. 1, parts being broken away to show the blast equalizing device arranged in the opening between the fan and the separating 35 chamber. Fig. 3, is a view similar to Fig. 2, showing the preferred form of said blast equalizing device; and Fig. 4, is a side elevational view of the machine showing the means whereby said blast equalizing device 40 may be adjusted.

Similar letters and characters of reference indicate similar parts throughout the views.

The standards C C disposed at the corners 45 together with the housing therebetween constitute the framework of the machine. D indicates a hopper or bin, open at the top and provided with an inclined bottom, into which the mixture to be acted upon is introduced and whence it descends by gravity 50 to the breast or retarding strip D³, which latter extends transversely the width of the hopper. An adjustable sliding gate D¹ controls the outlet of the hopper, and a rotary 55 feeding device D² provided with radial

wings is pivotally mounted immediately above the retarding strip D³ and is adapted to coöperate therewith in feeding the mixture in a stream of regular and uniform volume into vertical separating chamber F.

60

Located below the hopper is the blast fan A inclosed in a casing B having lateral air receiving vents B⁴. An opening E, provided in the lower front portion of the casing and extending transversely the width 65 of the fan, communicates with the separating chamber F at such an angle as to direct the blast upwardly therein. The bottom of the separating chamber F is preferably formed by a continuation of the lower peripheral portion of the fan casing and the same is made to slope downwardly and forwardly so as to direct the grain which passes through the air current into a duct F² whereby it is discharged into the collecting trough 70 F⁵ and thence by means of a pivoted deflecting chute F⁶ into a box or other suitable receptacle placed under the machine. Such portions of the mixture, as cockles, chaff, etc., which are lighter than the grain and 75 fail therefore to pass through the air current, are blown upward to a point near the top of the machine where they receive a forward deflection and are thus caused to descend into the collecting trough F³ and are 80 thence conducted out of the machine and into any suitable receptacle by the transversely inclined spout F⁴.

F¹ indicates an opening in the top of the machine through which the blast escapes 85 after having performed its work.

It not infrequently occurs that mixtures contain an unusually large proportion of foreign materials, or that on account of the same being wet or damp the foreign materials are in a greater or less degree of adherence with the grain, and it is obvious that in these cases, a considerably stronger blast is required for thorough cleaning than would be ordinarily be called for. Such a 100 blast however in the absence of some preventive device, would have the effect of blowing not only the foreign material but also a large portion of the grain into the trough F³ instead of allowing the same to descend and 105 settle into the grain receptacle. In order to meet and overcome this difficulty, I provide on the upper end of the front wall or partition of the separating chamber F a movable extension or plate H which is pref- 110

erably secured to said partition or to the lateral walls of the machine adjacent thereto by a pivot H^1 . Said pivot is preferably made rigid with said plate, and one of the 5 ends thereof projected through one of the lateral walls of the machine, and a suitable device for turning attached thereto, whereby the plate may be readily adjusted by the operator and may be thus deflected, either 10 rearwardly into the separating chamber to restrict the same and reduce the area of the upper opening thereof or forwardly toward the front of the machine to restrict the passage into the trough F^3 . A window I of 15 glass or other transparent material is preferably set in the upper portion of the front wall of the machine to enable the operator to observe the action of the blast on the mixture and thus determine upon the proper 20 adjustment of the plate.

As machines of this kind are adapted to be operated by hand as well as by power, it becomes likewise necessary to supply some compensating device in order to maintain a 25 blast of uniform pressure under varying degrees of velocity. This object I attain by means of a valve or gate J adapted to automatically control a relief opening B^2 formed in the periphery B^1 of the fan casing. Preferably I locate this valve at the bottom of the casing and immediately in the rear of the point where the latter gives on to the inclined bottom of the separating chamber, and mount the same to vibrate through a 30 limited arc by means of a pivot J carried in bearings J^2 . To hold the valve in closed position against any predetermined degree of air pressure, I preferably employ a counter-balance weight K^1 adapted to be adjusted at 35 any point upon a rearwardly extending slide rod K by means of a set screw K^2 .

In machines of this class, fans having wide blades are generally employed, and the air receiving openings are, as in this instance, 40 commonly located in the lateral walls of the fan casing. In operation, the result is, as may easily be understood and readily observed that the blast pressure becomes unevenly distributed across the width of the 45 separating chamber, the same being strongest at the sides of the chamber and weakest at the center. To obviate this defect and equalize the blast pressure I provide on the upper side of the mouth of the fan opening 50 E a depending lip or plate B^3 (see Fig. 2,) so formed as to make the opening E widest at the center and narrowest at the ends of the fan. This equalizing lip may be of any desirable contour, and may be made of two or 55 more parts rendered adjustable by suitable means from the outside of the machine. This device as shown in Fig. 2, may be formed by continuing the cylindrical wall B^1 of the fan casing into the opening E and 60 providing in the lower edge thereof an an-

gular recess having its apex at a point substantially central of the opening. But I have found that better results may be secured by the adjustable construction shown in Figs. 3 and 4, wherein plates b are movably attached to the wall B^1 of the fan casing by pivots p , are adapted to be rotated through a limited arc in a plane parallel with the axis of the fan to increase or decrease the angle formed by the lower edges 70 thereof and thus regulate the size and shape of the opening E . The plates b project through slots s cut in the side-walls of the machine and are adapted to be securely held in any desired position by means of set-screws t passing through arc-shaped slots o in the ends of the plates and threading into lugs r . It not infrequently occurs that one side of the fan takes in the air more rapidly 75 and in greater volume than the other, and this form of the regulating device is especially useful in such cases, since it is obvious that either one of the plates b can be moved independently of the other, and one side of the opening E can therefore be more restricted than the other. 80

The operation of this machine is as follows: The mixture to be cleaned is placed in the hopper D , whence it descends by gravity to the retarding strip D^3 , over which it 85 is conveyed and fed in a thin uniform stream into the separating chamber F , by the action of the rotary feeding device D^2 . Here it meets the blast from the fan A which blows the cockles, chaff, etc., upwardly toward the 90 top of the machine, and permits the grain which is heavier than the foreign material to settle to the bottom of the chamber. At a point near the top of the machine the foreign material is deflected and caused to descend into the trough F^3 , whence it is conveyed by the spout F^4 into a receptacle placed at the side of the machine. The grain meanwhile settles into the trough F^5 and is directed by deflecting chute F^6 into 95 another receptacle under the machine. Should the mixture be wet or otherwise heavy, the velocity of the fan may be increased and the blast pressure thus augmented, while the passage leading to the 100 trough F^3 may be constricted by deflecting the plate H toward the front of the machine to insure the return to the separating chamber of any particles of grain which may be blown out of the top thereof. In the case 105 of light mixtures or those containing unusually large proportions of foreign material, plate H is deflected rearwardly or into the course of the blast thus restricting the upper opening of the separating chamber and 110 subjecting the mixture to a very thorough action of the air current. In case the velocity of the fan should be suddenly increased during the course of any particular 115 operation of the machine, the blast pressure 120

125 130 135 140 145 150 155 160 165 170 175 180 185 190 195 200

is automatically maintained at a uniform degree of strength by the operation of the compensating valve *J*, which may be adjusted to withstand any predetermined degree of pressure, after which it will automatically open and allow a portion of the blast to escape through the opening *B²* in the fan casing.

Having described my invention what I claim as new and desire to secure by Letters Patent, is:

1. In a grain separator, the combination with a cylindrical blast fan having air-receiving openings at the lateral ends thereof and a transverse discharge opening extending from end to end of the fan formed in the inclosing casing thereof, of a blast regulating device comprising two plates movably pivoted to the central part of said casing adjacent said discharge opening and adapted to constrict the same, slots in the side walls of the separator through which said plates

extend, and means whereby said plates may be adjusted, the one independently of the other from the outside of the separator, so 25 that one side of said discharge opening may be restricted independently of the other.

2. In a grain separator, the combination with a cylindrical blast fan having air-receiving openings at the ends thereof and a 30 transverse discharge opening in the cylindrical wall thereof, of a blast regulating device comprising two plates pivoted to the central portion of said wall adjacent said discharge opening and adapted to rotate independently of each other through a limited arc in a plane substantially parallel with the axis of said fan, and means for adjustably securing said plates at any point in said arc. 35
